(57) **CLAIM**

The ornamental design for a blood pressure measuring apparatus, as shown and described.

DESCRIPTION

FIG. 1 is a front, right side, top perspective view of a blood pressure measuring apparatus showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a rear, left side, bottom perspective view thereof;

FIG. 9 and is a front, right side and top perspective view thereof with the cuff stored; and,

FIG. 10 is a rear, left side and bottom perspective view thereof showing the state in which a rear side portion is slid and batteries are stored.

The broken line showing of the cuff and batteries in FIGS. 9 and 10 is included for the purpose of illustrating purposes only and forms no part of the claimed design.
